EUGEN REISZ, OF BERLIN-DAHLEM, GERMANY.

DIAPHRAGMLESS MICROPHONE.

Application filed November 12, 1925, Serial No. 68,685, and in Germany September 19, 1925.

Diaphragmless microphones with a carbon-filling are known in which coal dust alone is placed in box-like receptacles or grains of coal are moulded, by admixture of 5 clay and certain liquids or salts into a plastic mass on which the sound waves of the air act.

These microphones do not however possess any advantage over the diaphragm microphones because their sensitiveness over a range of frequencies of from 100 to 7000 vibrations per second (such as is normally required) is not constant, that is to say, even in these arrangements definite frequencies are accentuated. This fact is shown by the following consideration.

When coal dust is used without a binding agent the spaces between the grains of coal form a passage for the sound waves and, 20 more especially, for the sound waves with low frequencies, so that the sensitiveness increases with the frequency and then decreases again owing to the deleterious shunt effect of the lower layers. When a binding 25 agent is used, the particles of coal no longer oscillate independently of each other but form a coherent oscillating mass which must possess resonance points in exactly the same way as a carbon diaphragm.

According to the present invention, these disadvantages are overcome by using a mixture of coarse and molecularly fine coal dust as a filling material and piling this mixture into a vibration-free receptacle to such a 35 height that the sound waves of the lowest frequency occurring are completely absorbed in the filling, the whole of the sound-energy being thus allowed to exert its pressure action.

Figure 1 shows a front view of the microphone with the insulating film covering the carbon chambers, the frames supporting the film and the grid plate removed.

Figure 2 shows a horizontal section of the 45 microphone.

Figure 3 shows in a conventional representation, the arrangement of the carbon grains and the two electrodes.

Figure 4 is a characteristic curve showing 50 the proportion of the frequencies of the sound waves to the amount of the change of resistance.

Figure 5 shows a similar curve for varied heights of the pile of carbon grains.

Figure 6 shows a similar curve for varied

size of the grains of the carbon dust or powder.

Figure 7 shows a curve for a low height of the carbon powder for high frequencies.

Before describing a constructional form 60 of apparatus according to the present invention, I will first explain, with reference to Figures 3 to 7 of the accompanying drawings, the operation of a diaphragmless microphone with a contact powder filling. 65

If a vibration-free receptacle (see Figure 3) be taken, in which two fixed electrodes are provided for the supply of current and coal dust be spread in the chambers between these electrodes, a microphone will be obtained the operation of which is graphically represented by curves as in Figures 4 and 5. For a given size of carbon powder granule and when the powder is piled up in the chamber to a certain height the characteristic curve 75 shown in Figure 4 is obtained. Along the abscissa are set out the periodicities of the sound waves which excite the microphone and along the ordinate, the sensibility values, that is to say, the magnitudes of the 80 variations of resistance. If the height to which the powder is piled up be varied, the dotted series of curves (see Figure 5) will be obtained according to the increase in the thickness of the layer of granules, while a 85 decrease of such thickness will be represented by the dot and dash curves.

A similar displacement of the curves also takes place, as shown in Figure 6, if the size 90 of the grains of the carbon powder be varied and with an increased size of granule the original curve 1 is changed into curve 2.

These phenomena, which are also confirmed by exhaustive experiments which the applicant has made are explained by the fact 95 that the sound waves with the lower frequencies pass to a great extent through the interstitial spaces between the carbon powder granules and, therefore, do not produce any variation of pressure on the grains themselves. On the other hand, these interstitial spaces offer a very high resistance to the sound waves with the higher frequencies, so that these sound waves are completely absorbed even in the uppermost layers of powder and the lower layers then constitute a 105 deleterious shunt to that portion of the carbon powder which is sensitive to changes of resistance.

Thus, in the range of musical frequencies, 110

which extends to 7000 vibrations per second, it is evidently necessary that the carbon powder be piled into the granule chamber to a very small height only. The obtention of a like degree of sensitiveness for the lower limit, i. e., about 100 vibrations per second, can only be achieved when the powder is piled in to a small height provided that steps be taken to ensure that the interstitial spaces between the grains of carbon are closed up. According to the present invention, this is effected by using material having granules of various different sizes, varying say from about 1 mm. down to the very finest pulverulent molecular powder, because it is only with such exceedingly fine material that the interstitial spaces can be completely closed against passage of the sound waves. When such material is used as contact powder for the constructional form of the microphone shown in Figure 3, there results a characteristic curve, shown in Figure 7, which runs in a straight line over a sufficiently wide range of frequency.

25 The same effect could be obtained by the use of very fine powder alone but for the fact that such powder has the property of caking together, thus rendering the desired individual oscillation of the separate grains illusory.

In the constructional form of the microphone shown in Figures 1 and 2, the layer of carbon is arranged vertically on the front of a fixed vibration free body e. g., a block *a* of marble. The fixed electrodes *b*, of carbon or of a non-oxidizable metal, which form the connection between the carbon powder and the conductor wires (not shown) are fixed in two deep troughs *h* in the marble block *a*, in such a way that their free external surfaces are entirely covered by the contact powder *c*. The attachment is effected for example by providing the electrodes *b* with screws *o* which are screwed into heads *k* of the screw bolts *i* which heads are conformed to the shape of the electrodes. These bolts *i* pass through the body *a* and are held on the reverse side thereof by nuts *l* which serve at the same time, to carry the current.

50 The two lateral deep troughs *h* merge at the front of the body *a* into the granule chamber *g*, which is exposed to action of the sound waves and is made very flat, so that the layer of powder may be equally sensitive to variations of pressure for all the various frequencies that occur. The entire chamber is covered in at the front by a thin skin *f* of rubber, which keeps the powder under a fixed pressure when the chamber is in a vertical position.

The use of a rubber skin for preventing the carbon granules from falling out is known, but in the arrangement herein described it serves a further purpose for, by reason of its stretched condition, it increases

the pressure under which the contact grains are maintained and makes the mass of powder perfectly "sound proof" even when a very thin layer is used. This rubber skin is held by a grid plate *n* (of fabric, gauze or the like) provided with a projecting rim *m*.

It is especially important also that the fixed electrodes shall not be attacked by the sound waves; otherwise the electrode rods begin to oscillate, whereby resonance effects are produced in the system.

In the practical constructional form shown in Figure 1, there is arranged, above the actual granule chamber, a subsidiary chamber *p* which can be closed by means of a plug *q* and the purpose of which is to supply the amount of powder required to keep up the constant pressure when the contact powder in the main chamber settles down with lapse of time.

I claim:

1. In a microphone, a vibration free insulating base, a pair of fixed electrodes mounted therein, a layer of contact material extending between and over said fixed electrodes, said contact material consisting of a mixture of coarse grained and fine dust or powder filling the interstices between the grains and flexible means for holding and pressing the grains together with a constant normal pressure.

2. In a microphone, a vibration free insulating base having a chamber, a pair of fixed electrodes mounted therein in the base, a layer of contact material in the chamber and extending over said fixed electrodes, said contact material consisting of a mixture of granules and fine dust or powder filling the interstices between the granules and a flexible stretched skin of an insulating material extending over said layer of contact material and holding the same in said chamber with a constant normal pressure.

3. In a microphone, a vibration free insulating base, provided with a chamber having depressions at opposite ends, a pair of elongated fixed electrodes in the depressions of the said base, a layer of contact material in the chamber and extending between and into said depressions, so as to partially surround said electrodes, said contact material consisting of a mixture of granules and fine dust or powder filling the interstices between the granules and flexible means for holding and pressing the grains of the contact material together with a constant normal pressure.

4. In a microphone, a vibration-free insulating base provided in one face with a chamber having recesses at opposite ends, a pair of elongated fixed electrodes housed in the said recesses, a filling of contact material in said chamber and extending into said recesses, so as to partly surround said electrodes, a flexible stretched skin of an insu-

lating material extending over said filling, and a grid secured to the base and securing the skin in position.

5. In a microphone, a vibration-free insulating base, a granule chamber formed therein, trough-like recesses in the bottom of said granule chamber and extending across opposite ends thereof, elongated electrodes housed in said trough-like recesses, electrical conducting means extending through said base to said fixed electrodes, a layer of contact material filling said granule chamber and extending into said recesses and partly around said fixed electrodes, a flexible skin of an insulating material stretched over said granule chamber, and means whereby the chamber is kept filled.

6. In a microphone, a vibration-free insulating base, a granule chamber formed therein, trough-like recesses in the bottom of said granule chamber and extending across opposite ends thereof, elongated electrodes housed in said trough-like recesses, electrical conducting bolts extending through said base and having heads fitting upon and secured to the electrodes, a contact filling in the granule chamber and the trough-like recesses, and partly surrounding the electrodes, flexible means arranged to close said granule chamber, and a grid plate having a rim and secured to the base and securing the flexible means in place.

7. In a microphone, a vibration-free insulating base, a granule chamber formed therein, trough-like recesses in the bottom of said granule chamber and extending across opposite ends thereof, fixed electrodes housed in said trough-like recesses, electrical conducting means extending through said base to said fixed electrodes a granular contact filling for the granule chamber and the trough-like recesses, said filling consisting of a mass of coarse granules having their interstitial spaces completely filled by molec-

ularly fine powder and flexible means arranged to close said granule chamber and to exert a constant normal pressure on said filling.

8. In a microphone, a vibration-free insulating base, a granule chamber formed therein, trough-like recesses in the bottom of said granule chamber and extending across opposite ends thereof, fixed electrodes housed in said trough-like recesses, electrical conducting means extending through said base to said fixed electrodes, a layer of contact powder filling said granule chamber and extending into said recesses and around said fixed electrodes, flexible means arranged to close said granule chamber and to exert a constant normal pressure on said filling, an auxiliary store of contact powder in the insulating base and means for admitting contact powder from said auxiliary store to the granule chamber.

9. In a microphone, a vibration-free insulating base, a granule chamber formed therein, trough-like recesses in the bottom of said granule chamber and extending across opposite ends thereof, fixed electrodes housed in said trough-like recesses, electrical conducting means extending through said base to said fixed electrodes, a layer of contact powder filling said granule chamber and extending into said recesses and around said fixed electrodes, flexible means arranged to close said granule chamber and to exert a constant normal pressure on said filling, an auxiliary contact powder chamber in said insulating base, an opening from said auxiliary chamber into the granule chamber, an opening from said auxiliary chamber to an exterior surface of the base and means for closing said last named opening.

In testimony whereof I have signed my name to this specification.

EUGEN REISZ.
